(57) **CLAIM**

The ornamental design for a coin container, as shown and described.

DESCRIPTION

FIG. 1 is a top, front, left side perspective view of a coin container showing my new design in a used condition with identical coin containers shown in broken lines that form no part of the claimed design;

FIG. 2 is a front, bottom, left side perspective view thereof; FIG. 3 is a front elevational view thereof, the opposite rear elevational view, left side elevational view, and right side elevational view all being identical;

FIG. 4 is a top plan view thereof; and,

FIG. 5 is a bottom plan view thereof.
